UNITED STATES PATENT OFFICE.

CHARLES J. PEMBROKE, OF ROCHESTER, NEW YORK.

INTERNAL-COMBUSTION ENGINE.

1,174,440.

Specification of Letters Patent. Patented Mar. 7, 1916.

Application filed August 3, 1910. Serial No. 575,282.

To all whom it may concern:

Be it known that I, CHARLES J. PEMBROKE, of Rochester, in the county of Monroe and State of New York, have invented 5 certain new and useful Improvements in Internal-Combustion Engines; and I do hereby declare the following to be a full, clear, and exact description of the same, reference being had to the accompanying 10 drawings, forming a part of the specification, and to the reference numerals marked thereon.

My present invention relates to engines and more particularly to internal combustion or explosive engines, and it has for its 15 object to provide such an engine with a reliable and efficient lubricating system.

A further object of the invention is to lubricate a multiplicity of working parts 20 with the same body of oil, used over and over again, means being included for freeing the oil from impurities gathered during its flow through the lubricated parts.

The improvements are further directed to 25 toward utilizing the lubricating system in silencing much of the usual noise and clatter of the engine.

To these and other ends the invention consists in certain improvements and combinations 30 of parts, all as will be hereinafter more fully described, the novel feature being pointed out in the claims at the end of the specification.

In the drawings: Figure 1 is a side elevation 35 of a multiple cylinder engine constructed in accordance with and illustrating one embodiment of my invention, the main reservoir of the lubricating system being shown in section. Fig. 2 is an end view of the front cylinder, the view being in transverse section through the crank case compartment of that cylinder. Fig. 3 is a longitudinal central section through the same cylinder, crank case, valves and valve operating mechanism. Fig. 4 is a transverse section 45 through the cam shaft and one of the valves showing the same in detail and much enlarged, and Fig. 5 is a detail section taken substantially on the line 5—5 of Fig. 3, 50 showing the oil pump that is utilized in the present embodiment of the invention.

Similar reference numerals in the several figures indicate similar parts.

An oiling system embodying my invention 55 is in contradistinction to that form known as the splash system, wherein the connecting

rods coming in contact with a quantity of oil in the lower half of crank case, throw more or less of it upward into the piston swept portion of the cylinder. In the splash 60 system of lubrication the amount of oil delivered to the working parts depends upon the depth the connecting rods and crank webs are allowed to dip into the oil and unless the depth of oil be maintained at a 65 uniform level the quantity of oil delivered varies under different conditions. Further difficulties are attributed to the splash system of oiling, because it is impossible to determine the quantity of oil in the crank 70 case and owing to the differences in the consistency of various oils and the effects of weather conditions thereon, it is practically impossible to maintain proper lubrication of the parts at all times.

In carrying out my invention all forms of oilers, grease cups, small pipes, fine mesh strainers, etc., that are liable to become clogged and get out of order and out of adjustment are dispensed with.

In practice I employ but one feed pipe 75 of large diameter, insuring a free uninterrupted flow of oil at all times. By the arrangement of the parts which I employ the valve stems are at all times submerged in 80 a bath of oil, the working teeth of all the cam shaft gears are either running in an oil bath or receive a liberal supply of oil at all times.

The engine illustrated in the present embodiment of the invention is one expressly 85 designed for motor vehicles and is shown beneath the hood 1 of such a vehicle, which hood is joined to a hollow dash 2 that, in the present instance, forms the main oil 90 reservoir of the lubricating system substantially along the lines of the invention disclosed in my prior application, Serial No. 521,318, filed October 6, 1909.

As to the general features of the engine 95 itself, it comprises a series of cylinders 3 bolted to the crank case 4, the latter being divided into upper and lower halves 5 and 6, each common to all of the cylinders. Internally, the crank case is divided into a 100 plurality of crank chambers 7 by upper webs or walls 8 on the upper half 5 and lower webs or walls 9 corresponding thereto on the lower half 6. The bearings 10 of the crank shaft 11, common to all the compartments, are hung by bolts 12 from the upper webs 8, as shown in Fig. 3. The cranks

are indicated by 13, the connecting rods by 14 and the pistons by 15.

In the practice of my invention, the quantity of oil is introduced and held in the main reservoir 2 (Fig. 1) and distributed therefrom to the main bearings of the crank shaft, the cranks, cylinders and other working parts generally by the pipe 35 and conduits 16 arranged on the lateral walls of each crank case compartment above the level of the axis of the crank shaft. The conduits 16 are formed in the present instance by upwardly turned integral flanges on the upper half 5 of the crank case casting, and leading 15 from these conduits across each main crank bearing 10 is a conduit 17 preferably of similar design, but inclined downwardly toward the bearing and provided at a central point over the same with an opening or passage 20 18, shown in Fig. 3, leading to the interior of the bearing. One, if not both, of the conduits 16 is extended through all of the compartments of the crank case to permit a portion of the oil being delivered to each one of 25 the conduits 17. To insure an even distribution of the oil from the common conduits 16 to the conduits 17, the latter communicate with the conduits 16 through restricted openings 19, shown in Fig. 3, each of which 30 is considerably less than the capacity of the conduit, thus preventing the flow of oil from turning bodily into the first conduit it reaches.

The quantity of oil delivered through the 35 openings 19 to the conduit 17 is in excess of that required to lubricate the crank shaft bearings, hence the surplus oil will overflow the flanged side of said conduit onto the crank web 13, from which it is thrown by 40 centrifugal force, an equal quantity going in every direction, by which means the cylinder is oiled. The quantity of oil reaching the cylinder is of the same proportion to the total amount of oil thrown from the webs as 45 the diameter the cylinder bears to the circumference of the circle through which the oil is thrown.

A vertically extending tubular jacket 20 is joined to and extends upwardly from the 50 crank case and opens into the interior thereof. In the upper and lower ends of the jacket are bearings 21 and 22 of a jack shaft 23 which it incloses, the latter being driven, through the medium of a gear 24 on its lower 55 end meshing with a beveled gear 25 on the crank shaft 11, while at its upper end, above the bearing, is a similar beveled gear 26 in a gear case 27 that connects the jacket 20 with a similar tubular jacket 28 extending 60 across the cylinder heads of the engine, the said gear case being preferably formed as shown by constituent parts on the jackets. The gear 26 on the jack shaft drives a gear 29 in the gear case mounted on the end of a 65 cam shaft 30 and closed by the jacket and

having end bearings 31 and intermediate bearings 32 contained and supported therein.

The opposite end of the jacket 28 communicates at an elevated point with the interior of the main oil reservoir 2 by suitable piping 33 which discharges at 34 against a lateral wall of the reservoir, while a pipe 35, arranged adjacent to the opposite wall, leads from a point 36 elevated substantially above the bottom of the reservoir to the interior of the crank case at 37, the last named point being shown in Fig. 2 to be so arranged that the discharge from the pipe is received in one of the interior troughs 16, before described, and forming part of the 75 interior lubricating arrangement of the crank case.

A pipe 38 forms a circulating passage for conducting oil from the bottom of the crank case to the cam shaft jacket 28 which it preferably joins at a point near the front end thereof, as shown. In this pipe is arranged a pump, the same being in the present instance a gear pump comprising, a pair of intermeshing gears 39 and 40 inclosed within a casing 41 and driven by a shaft 42 that enters the jacket 20 and is provided with a worm gear 43 meshing with a worm 44 on the jack shaft 23, all as shown in Fig. 5. The connection of the lower end of the pipe 38 with the crank case is preferably not direct, but through the medium of an overflow chamber 45 common to all the crank case compartments 7 with which it has individual communication through passages 46 in nipples 47 that project inwardly from a wall of each crank case compartment. These nipples form the intake points of the circulating system and are designed to project, as they do, above the bottom of the crank case and outwardly from the walls in order that the impurities of the oil that settle toward the bottom will not pass out therethrough and neither will the oil, as it runs down from the walls of the crank case until it has joined the main body of oil and had a chance to settle. These nipples are located in each compartment of the crank case with their open ends positioned so as to maintain the level of the oil in the several compartments at a point below the bottom of the circle described by the cranks, thus preventing the latter from splashing in these bodies of oil.

Returning to the region of the cam shaft, 120 the valves 48 of the engine are carried by valve casings 49 fitted within and preferably easily removable from the cylinder head 50 into which they are secured, in the present instance, by threaded rings 51, all as clearly shown in Figs. 3 and 4. Between the clamping rings 51 and the valve casing are interposed nuts 52 through which are threaded or otherwise secured the lower ends of collars 53 on the cam shaft jacket 28 125

constituting extensions thereof that support the jacket and the parts carried thereby and form chambers 54. Through these chambers pass the stems 55 of the valves that 5 project from the casing 49 and are provided with cap pieces 56 having pockets 57 for balls 58 with which contact the cams 59 on the cam shaft to operate the valves as usual. Webs 60 at the bases of the collars constituting walls of the chambers 54 form guides for the heads 56 of the valve stems, these webs being preferably cut by perforations or passages 61 to form communication between the chambers 54 and the jackets 28, 10 while mounted on the stems below the heads are disks forming pistons 62 operating in the chambers. A coil spring 63, interposed between the piston or enlargement and the valve casing in each instance, operates to 15 return the valve, or at least to actuate it in one direction, and a suitable gland 64 surrounds the valve stem bearing to prevent an excess of oil from flowing into the latter around the valve stem though a sufficient 20 amount is admitted to well lubricate the stem.

It will be seen that when the engine is in operation the oil will be forced by the pump 39, 40, assisted by gravity, from the 25 main reservoir 2 through the pipe 35, which it enters at 36 well above the bottom of the reservoir and the sediment and impurities which have settled there, into the crank case at 37 where it is delivered to the troughs 16. 30 From the troughs it finds its way, by way of the crank shaft bearings 10, as previously explained, and otherwise, to the bottoms of the various crank casing compartments 7 from whence it is again taken up through the nipples 47 and by means of the pipe 38 35 is conveyed to the crank shaft 28. From thence it passes through the jacket and through the various intermediate bearings 32 therein for the crank shaft 30 to the pipe 33 and out at 34 back into the reservoir 2, the discharge being against the opposite wall of the said reservoir from that adjacent to which is arranged the end 36 of the pipe 35 so that it cannot drop directly into the 40 latter, but must first mix with the bulk of the oil where it has a chance to settle and clear itself of impurities. But with the arrangement shown not all of the flow passes from the cam shaft jacket 28 back to the 45 crank case by way of the main reservoir 2. There is also a current through the bearing 31 at the end of the cam shaft and jacket into the gear case 27 and from thence through the jacket 20 of the jack shaft 23 50 and through the bearings 21 and 22 thereof back into the crank case at the forward end thereof. These bearings, however, particularly when of the ball bearing type, are rather open and might often permit too free 55 a flow of oil in this direction. I; therefore,

provide collars 65, 66 and 67 on the ends of the cam shaft 30 and jack shaft 23, respectively, which are spaced at their peripheries from the inner walls of the jackets 28 and 20 so that only a restricted communicating passage is allowed which slows up the current, the object, being to keep both jackets full of oil all the time so that the moving parts therein will be entirely immersed. To further this end, the passage 75 formed by the spacing of the collar 65 on the cam shaft is greater than that formed by the upper collar 66 on the jack shaft and that in turn is greater than the passage at 67 by which grading in the spacing of the 80 collars, and the capacities of the passages they form, the desired result is accomplished, as will be understood.

It will be recognized at once that the main reservoir 2 is not indispensable to practical 85 results, being provided more for the purpose of balancing the distribution of the oil and insuring the presence of an adequate quantity in the system as well as offering a convenient point of introduction for replenishing the supply. In the event that the reservoir 2 is not used, it is perhaps best to let the pipe 38 discharge into the cam shaft jacket 28 at the point at which the pipe 23 is in the present instance shown to 90 be connected, or in other words, at the extreme inner end of the jacket so that the flow back to the crank case will be directed through all of the intermediate bearings 32 of the cam shaft. The jacket 28 being thus 95 constantly filled, it acts as a reservoir for supplying the chambers 54 in which the valve stems operate and into which entrance is freely gained through the passages 61. The oil thus inclosed in the chamber 54 not 100 only serves to lubricate the valve stems but also acts as a cooling agent that does more in that it makes such lubrication extremely effective and the reciprocations of the pistons 62 on the valve stem churn up the 105 body and cause it to circulate with that in the jacket 28 so that overheating is prevented.

On the whole, it will be seen that the working parts within the crank case will be 110 well lubricated by the oil thrown from the crank webs, while the crank shaft bearings will receive the benefit thereof and also profit by the supply of oil insured to them through the trough 16 and conduits 17. 115 The other working parts of the engine will be running in oil, including the jack shaft, their communicating gears and the valve stems and the oil is not only used over and over again to the end of economy, but during its circulation it passes through all of the bearings and wearing parts cleansing them thoroughly, yet it is robbed of the impurities thus collected before again traversing the same course by being allowed to 120 125 130

- settle in the main reservoir 2 or in the bottom of the crank case. Furthermore, besides the lubricating function, it acts as a cooling agent for the valve mechanism, as pointed out, and as a muffler for silencing the moving parts. This last property is of particular value with respect to the valve mechanism, the clatter of the valves, their springs 63 and the contact of the cams 59 with the valve stems, being well known to constitute much of the noise attendant upon the running of an internal combustion engine, especially that type known as the valve in head motor, as it not only does away with the difficult oiling feature of this type of motor, but also dispenses with the use of several objectionable parts, such as push rods, pinned rollers, walking beams, grease cups, etc.
20. The inclosing of the cam shaft 30 and the valve operating devices in an air tight, oil tight and dust proof casing containing a liberal supply of lubricating fluid, not only renders the valve mechanism noiseless when in operation but obviates many disadvantages otherwise encountered, such as insufficient lubrication, inability to cool the valve cage heads and loss of temper in the exhaust valve spring. A still further advantage is obtained in the arrangement of parts I have adopted in that I am able to obviate the possibility of the pistons sucking air through the spaces surrounding the valve stems when the latter become worn, a circumstance which materially affects the operation of an explosive engine when it is operated with a partly closed throttle. The valve parts being surrounded with oil, the entrance of the air into the pistons at these points is prevented and the motor is permitted to run at low speeds with a perfectly timed movement, even after the motor has been subjected to long continued service.
- I claim as my invention:
45. 1. The combination with a plurality of crank case compartments adapted to serve as oil reservoirs and a crank shaft extending through the compartments and having bearings in the end walls thereof, of an open trough extending along the side walls of the compartments at a higher level than the axis of the crank shaft and provided with a restricted opening and an inclined conductor leading from the restricted opening in said trough across the end wall of each compartment and provided with an opening in its bottom leading to the crank shaft bearing in that wall.
2. The combination with a crank case forming a reservoir for oil, a crank shaft, 60 and a cam shaft driven by the latter, of a jacket for the cam shaft and its bearings, an oil circulating system including the jacket and crank case and means for effecting a flow of oil through said system from 65 the crank case to the jacket and back again.
3. The combination with a crank case forming a reservoir for oil, a crank shaft, 70 and a cam shaft, of a jack shaft for transmitting motion to the cam shaft from the crank shaft, a jacket for the jack shaft and its bearings communicating with the interior of the crank case, a jacket for the cam shaft and its bearings communicating with the jacket of the jack shaft, an oil conduit 75 leading from the crank case to the cam shaft jacket and means for effecting a flow of oil from the crank case, through the conduit to the cam shaft jacket and back to the crank case through the jack shaft jacket. 80
4. The combination with a crank case forming a reservoir for oil, a crank shaft and a cam shaft, of a jack shaft for transmitting motion to the cam shaft from the crank shaft, a jacket for the jack shaft and its 85 bearings communicating with the interior of the crank case through a restricted opening, a jacket for the cam shaft and its bearings communicating with the jacket of the jack shaft through a further restricted 90 opening, an oil conduit leading from the crank case to the cam shaft jacket and means for effecting a flow of oil from the crank case, through the conduit to the cam shaft jacket and back to the crank case 95 through the jack shaft jacket.
5. The combination with a crank case forming a reservoir for oil, a crank shaft and a cam shaft, of a jack shaft for transmitting motion to the cam shaft from the crank shaft, a jacket for the jack shaft and its 100 bearings communicating with the interior of the crank case, a jacket for the cam shaft and its bearings communicating with the jacket of the jack shaft, an oil conduit 105 leading from the crank case to the cam shaft jacket and means for effecting a flow of oil from the crank case, through the conduit to the cam shaft jacket and back to the crank case through the jack shaft jacket, 110 the flow through the jackets being directed through bearings of the shafts they inclose.

CHARLES J. PEMBROKE.
